UNITED STATES PATENT OFFICE.

CHARLES L. ROBERTS, OF LOUISVILLE, KENTUCKY, ASSIGNOR TO THE AMERICAN TOBACCO COMPANY, OF NEW YORK, N. Y., A CORPORATION OF NEW JERSEY.

METHOD AND MACHINE FOR FLAVORING LEAF TOBACCO.

Application filed June 11, 1925. Serial No. 36,299.

This invention is an improvement in methods and machines for flavoring leaf tobacco, and more particularly in methods and machines for flavoring the finer particles of the leaf and the tobacco dust produced during the handling of the leaf.

In some of the procedures to which leaf tobacco is subjected in this conversion from the raw to the finished product, the leaves are flavored, usually by dipping into a suitable flavoring liquid, draining, and compressing to express the excess liquid.

Prior to the flavoring of the tobacco the large woody portion of the stem is removed. In the operation a relatively large quantity of tobacco dust, and fragments of a size too small to be successfully flavored by the usual methods are produced. These particles and the dust are tobacco of the same character and grade as the larger pieces, and are entirely suitable for use in the making of the products for which the larger portions are used.

In the usual method of flavoring, the tobacco leaves are passed through the flavoring liquid, by mechanical means, and they arrive at the expressing mechanism, usually a pair of cooperating wringer rollers, in a more or less bunched condition. The rollers ordinarily used are smooth surfaced, and they do not readily grasp bunched leaves. Unless the feed to the rollers is substantially uniform, they do not function to the best advantage, so far as a wholly mechanical operation is concerned, and the mechanical feed must be supplemented by manual manipulation.

One of the primary objects of the present invention is the provision of a method by the practice of which the smaller portions of the leaf and the tobacco dust may be flavored without dipping, to the same degree as the dipped portions, and agglomerated with the dipped portions for convenience in the further handling of the leaf.

Another object is the provision of a new and improved mechanism or machine for carrying out the process.

Another object is the provision of a mechanism so constructed and arranged that the agglomeration of the dry and the dipped particles will be of substantially uniform character.

Another object is the provision in such a mechanism of a construction of express-

ing rollers such that the rollers will effectively grip the leaves, whether they come in bunched or in segregated relation.

To the accomplishment of the foregoing, and such other objects as may hereinafter appear, the invention consists in the method, and in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereto: Fig. 1 is a longitudinal vertical section through a machine for carrying out the method.

Fig. 2 is an enlarged detail in section of the expressing rollers.

In the present embodiment of the invention, the improved machine for carrying out the method, includes a tank 1 for holding the flavoring liquid, which may be of any suitable or desired composition, and the tobacco to be flavored is fed into the tank at one end thereof, through an inclined chute 2. Only the larger portions of the leaf, such as the tips, separated in the manner shown and described in my copending application Ser. No. 36,298, of even date herewith, are fed through the chute 2.

The leaves are submerged in the liquid, and are driven therethrough, by means of a dipping drum 3, on a shaft 4, which is journaled transversely of the tank, near the discharge end of the chute 2. The drum has on its periphery longitudinally extending plates or vanes 5, which impart movement to the liquid in a direction away from the chute 2, and which engage the leaves that may float on the liquid, and submerges them therein.

Thus the drum provides for a very intimate mixture of the leaves and the flavoring liquid, so that every part of each leaf particle is touched with the liquid. After leaving the drum, the leaves pass beneath the lower end of an elevator, which removes them from the tank, carrying them over a drainage plate.

The carrier is composed of endless chains 6, supported by sprocket wheels 7 on shafts 8 and 9 journaled transversely of the trough, the shaft 7 being supported by the trough.

while the shaft 9 is arranged well above the same, and in rear of the shaft 8. As many chains as may be necessary are provided, the chains being in register, and they are connected by cross bars 10 at suitable intervals.

The cross bars carry tines or prongs 11, a number being provided for each cross bar, and arranged longitudinally thereof. The construction is such that the tines are swept 10 in succession through the flavoring liquid, just in rear of the dipping drum, and the chains are moved in such a direction, that the lower runs thereof move upwardly, and rearwardly from the tank.

15 A drain board or plate 12 is arranged in the rear of the carrier, in inclined position, and so positioned that the free ends of the tines on the lower run of the carrier move close to the surface thereof, but without contacting with said surface. The plate 12 is a 20 perforate plate as shown, and as the leaves are moved up the sloping plate by the tines or prongs, the excess liquid escapes, running down the plate, and through the perforations, back into the tank.

25 At its rear and upper end, the plate 12 has an extension 13, which inclines in the opposite direction to the plate 12. The drained, but still wet leaves pass over the 30 angle between the plates 12 and 13, dropping down over the rear face of the plate 13 into the grasp of the expressing mechanism.

35 The said mechanism includes a pair of rollers 14 and 15, arranged with their axes parallel, and with the axis of the roller 14 above and in rear of that of the axis of the roller 15. Each of these rollers comprises a 40 cylindrical body as shown, having a facing 16 of resilient material, with a high coefficient of friction, as for instance rubber. The rubber facing is corrugated longitudinally of each roller, to provide alternating 45 grooves and ribs, and the ribs of one roller register with the grooves of the other roller, so that in the normal position of the rollers there is an interlocking engagement between them.

50 Just above the roller 14, a chute 17 is arranged, in inclined position, the chute delivering to the upper surface of the roller 14 just in front of the axis thereof. The chute delivers onto the dipped and drained large 55 leaf particles, the fine particles and dust, which are produced in the handling of the tobacco, prior to the flavoring thereof, and which are showered onto the dipped portions, in a dry condition. This material is delivered in a stream, extending substantially 60 the full length of the roller 14, and falling into the grooves and onto the ribs thereof, is carried around and delivered upon the dipped tobacco, just prior to the expression of the excess liquid therefrom.

65 The stream delivered may be of any de-

sired thickness, and it will be evident that as the roller 14 turns, the finer particles of dust will be agglomerated with the dipped larger leaf particles by the pressure of the rolls, and will be simultaneously flavored, partly by absorption, and partly by the forcing of the excess liquid from the dipped tobacco into the dry tobacco.

The compressed or wrung tobacco is delivered by the rollers 14 and 15, onto a drum 75 18, having longitudinal extending radial plates 19. This drum rotates in the same direction as the lower roller, and as the leaf particles are delivered onto the plates thereof, they are carried over the drum, and dropped through a chute 20 into a suitable receiver.

The drums, shafts, and rollers are driven in any suitable manner from a prime mover not shown, and the tobacco is supplied to the chutes 2 and 17 in any desired manner. The product of the improved machine is an agglomeration of large and small particles, the small particles being compressed onto and into the larger particles, so that all are flavored, and the product is in a convenient shape for further processing.

The arrangement of rollers, having longitudinally extending alternating grooves and ribs, insures a firm grasp of the dipped tobacco, regardless of uniformity in the feed, that is the leaves may come in bunches, or in segregated relation, without effecting the grasp of the rollers in any manner. Furthermore the grooving of the rollers, provides pockets for receiving the dry leaf particles, and dust as they are showered down from the chute 17, and they function more satisfactory in the agglomeration of the dry and wet leaf. One of the rollers 14—15 is usually spring supported to yield away from the other.

I claim:

1. The method of flavoring tobacco leaves in large and small fragments, which consists in dipping the larger fragments in a flavoring solution, draining said fragments, showering the finer fragments in a dry condition onto the drained fragments, and afterwards squeezing to express the excess liquid and to simultaneously agglomerate the dry fragments with the dipped fragments.

2. In the method of flavoring leaf tobacco by immersion in a flavoring liquid, draining, and expressing the excess liquid, the step which consists in sprinkling on the dipped leaf, prior to the expressing, fine tobacco leaf particles and dust.

3. In the method of flavoring leaf tobacco by immersion in a flavoring liquid, draining, and expressing the excess liquid, the step which consists in agglomerating with the tobacco during the expressing masses of smaller particles of tobacco in a dry condi-

tion prior to their contact with the drained tobacco.

4. The method of flavoring leaf tobacco which consists in immersing the leaves in a flavoring liquid, draining, and working into the mass of leaves by expression masses of substantially dry tobacco leaf particles.

5. In a machine for flavoring leaf tobacco, including a dipping tank, a drain board, and a plurality of means to submerge and move the leaves through the liquid in the tank, and to move them over the drain board expressing rollers to which the drain board delivers, and means for showering finer leaf particles in a dry condition upon the dipped leaves, prior to their passage between the rollers.

6. In a machine for flavoring leaf tobacco, including a tobacco tank, a drain board, and a plurality of means to submerge and move the leaves through the liquid in the tank, and to move them over the drain board expressing rollers to which the drain board

delivers, and means to shower leaf particles and tobacco dust onto the upper roller at 25 the side adjacent to the drain board.

7. In a machine for flavoring tobacco, a pair of longitudinally corrugated expressing rollers arranged one above the other for expressing the excess liquid, and means 30 for showering finer leaf particles and tobacco dust in a dry state, onto the downwardly moving side of the upper roller.

8. In a machine for flavoring tobacco, a pair of co-operating corrugated expressing 35 rollers arranged one above the other with the corrugations of one fitting between the corrugations of the other, means for showering leaf particles and tobacco-dust in a dry state onto the downwardly moving side of 40 the upper roller and into the corrugations for the purpose specified.

Signed at Richmond in the county of Henrico and State of Virginia this eighth day of June A. D. 1925.

CHARLES L. ROBERTS.
